UNITED STATES PATENT OFFICE.

EDSON M. GASKILL, OF EDENTON, OHIO.

ROCKING-CHAIR CHURNING-MACHINE.

SPECIFICATION forming part of Letters Patent No. 233,500, dated October 19, 1880.

Application filed May 3, 1880. (No model.)

To all whom it may concern:

Be it known that I, EDSON M. GASKILL, of Edenton, Clermont county, State of Ohio, have invented a new and useful Improvement in 5 Rocking-Chair Churning-Machines, of which the following is a specification.

Figure 1 is a perspective view of the improvement. Fig. 2 is a side elevation, partly in section. Fig. 3 is a vertical cross-section of the 10 rack-bar, gear-wheel, and hinged arm, and Fig. 4 is a plan view of the gear-wheel.

Similar letters of reference indicate corresponding parts.

The object of this invention is to furnish a 15 churning-machine so constructed that it will be operated by giving oscillating movements to the chair upon which the operator sits.

The invention consists in constructing a churning-machine of a chair, a connecting-rod, 20 a pivoted upright, a rack-bar, a gear-wheel, a hinged arm having keeper and hand-screw, and a treadle, so that the churn-dasher can be operated by the oscillation of the chair, as will be hereinafter fully described.

25 A represents a chair, the rear legs of which are set in sockets or recesses formed in the floor or in blocks or plates attached to the floor.

To the lower part of a forward leg of the chair A is pivoted the lower end of an inclined 30 connecting-bar, B, the upper end of which is pivoted to an upright bar, C. The lower end of the bar C is pivoted to the floor, or to a support attached to the floor.

To the upper part of the upright bar C is pivoted the rear end of a bar, D, upon the inner 35 side of the forward part of which are formed rack-teeth to engage with the teeth of the gear-wheel E, attached to the upper part of the handle F of the dasher G.

40 The dasher G is formed of three (more or less) wings attached longitudinally to the handle F, and having longitudinal slots formed in their inner parts.

The lower end of the dasher-handle F revolves in a socket or step, H, attached to the 45 bottom of the churn I. The upper end of the dasher-handle F revolves in a socket in the lower side of the forward end of the arm J, the rear end of which is hinged to the upper 50 end of a standard, K, attached to the floor or to some other suitable support.

The hinged arm J is held from dropping below a horizontal position by a brace, L, rigidly attached to it, and which rests against the forward side of the upper part of the standard 55 K. The standard K is strengthened in position by a brace, M, attached to its upper part, and the lower end of which is attached to the floor.

To the pivoted upright C is pivoted the end 60 of the arm N, the other end of which is attached to or formed upon the bar O, which is bent into crank form, and is hinged at its ends to the floor, so that the arm N and crank-bar O may form a treadle or foot-lever to assist in 65 working the machine.

To the forward end of the hinged arm J is attached the end of a metal strap, P, which is bent downward and inward to form a keeper to keep the rack-bar D in place. The lower or 70 free end of the strap P projects inward far enough to pass beneath the gear-wheel E and prevent it from slipping down too far upon the dasher-handle F.

The rack-bar D is held against the gear-wheel E by a hand-screw, Q, which passes in 75 through the outer part of the strap or keeper P, so that its forward end may rest against the outer side of the said rack-bar D.

In using the machine the operator sits in the 80 chair A, takes hold of the pivoted upright C with one hand, and places his feet upon the treadle O N. The operator then tilts the chair A back, and at the same time presses against the upright C and treadle N O with his feet 85 and hand. As the operator ceases to press against the upright C and treadle N O his weight brings the chair A back to its former position. These movements give a reciprocating movement to the rack-bar D, and through 90 it to the churn-dasher G, bringing the butter in a very short time. By oscillating the chair A very slightly a slight reciprocating movement will be given to the dasher G, which will gather the butter very quickly and very thoroughly into a compact mass. The butter may then be removed from the churn in the usual 95 way.

Having thus described my invention, I claim as new and desire to secure by Letters Patent—

1. A churning-machine constructed substan-

tially as herein shown and described, consisting of the chair A, the connecting-rod B, the pivoted upright C, the rack-bar D, the gear-wheel E, the hinged arm J, and the treadle O 5 N, whereby a churn-dasher can be operated by the oscillation of the chair A, as set forth.

2. In a churning-machine, the combination, with a chair, A, and a churn-dasher handle, F, of the pivoted bar B, the pivoted upright C, 10 the pivoted rack-bar D, the gear-wheel E, the hinged arm J, and the standard K, substantially as herein shown and described, whereby the churn-dasher will be operated by the oscillation of the chair, as set forth.

15 3. In a churning-machine, the combination, with the pivoted upright C, that carries the

rack-bar D, of the treadle O N, substantially as herein shown and described, whereby the operator may use his feet to assist in operating the churn-dasher, as set forth.

20

4. In a churning-machine, the combination, with the rack-bar D and the hinged arm J, of the strap or keeper P and the hand-screw Q, substantially as herein shown and described, whereby the rack-bar is kept in place and in 25 gear with the gear-wheel E, attached to the dasher-handle F, as set forth.

EDSON MURY GASKILL.
